UNITED STATES PATENT OFFICE.

HERBERT H. SELLERS, OF OAKLAND, CALIFORNIA.

ADJUSTABLE FILING-CASE.

987,018.

Specification of Letters Patent. Patented Mar. 14, 1911.

Application filed July 28, 1910. Serial No. 574,379.

To all whom it may concern:

Be it known that I, HERBERT H. SELLERS, a citizen of the United States, residing at Oakland, in the county of Alameda and 5 State of California, have invented certain new and useful Improvements in Adjustable Filing-Cases, of which the following is a specification.

This invention relates to filing cases and 10 the principal object of the same is to provide a cheap yet durable structure which can be formed of card board or other suitable material, and in which a stop is provided and carried by novel guide strips so that 15 said stop can be readily adjusted.

In carrying out the objects of the invention generally stated above it will be understood, of course, that the essential features thereof are necessarily susceptible of changes 20 in details and structural arrangements, one preferred and practical embodiment of which is shown in the accompanying drawings, wherein:—

Figure 1 is an end elevation of the improved filing case. Fig. 2 is a vertical longitudinal sectional view taken on the line A—A, Fig. 1. Fig. 3 is a transverse vertical sectional view taken on the line B—B, Fig. 2. Fig. 4 is a top plan view, the cover being 30 removed. Fig. 5 is an enlarged detail sectional view of the bottom guide strip of the case.

Referring to the accompanying drawings by numerals, it will be seen that the improved case comprises a body the bottom 1 and sides 2 of which are integral, said body being preferably formed of cardboard that is bent to the desired shape. The forward end of the bottom 1 is upturned to provide 40 a flange 3 and the forward edges of the sides 2 are inturned to provide flanges 4, and said flanges have the front closure strip 5 glued or otherwise rigidly fastened thereto. The rear of bottom 1 is also provided with an 45 upturned flange 6 and the lower portions of the rear edges of sides 2 are provided with inturned flanges 7. Said flanges 6 and 7 have a lower guard strip 8 glued or otherwise rigidly fastened thereto. The upper 50 portions of the rear edges of sides 2 are also provided with inturned flanges 9, and said flanges have the upper guard strip 10 glued or otherwise rigidly fastened thereto. This structure provides a body having an open 55 end and top.

A guide strip 11 is held in parallel rela-

tion to the longitudinal center of the bottom 1 of the body by the spacer blocks 12. Said strip is preferably of wood and has its longitudinal edges provided with flat metallic wear strips 13. The sides 2 of the body are provided with horizontally arranged oppositely disposed guide strips 14 which are held in spaced relation to said sides by the blocks 15.

An abutment or stop 16 has its bottom edge provided with a forwardly projecting flange 17 and its side edges are provided with similar flanges 18, and said flanges 17 and 18 are connected by the corner fasteners 19. Said stop has a base opening 20 through which the bottom guide strip 11 extends and side openings 21 through which the side guide strips 14 extend. Said strips are passed through said openings and glued 75 or otherwise rigidly attached to their spacer blocks so that the flanges of the stop will be beneath said strips. A handgrip 22 is suitably attached to the rear surface of said stop 16 so that said stop can be readily adjusted on the guide strips.

A cover 23 is provided for the body, said cover being preferably of cardboard and having its side and end edges bent to provide the pendent flanges 24 and 25 which 85 engages over the edge of the body. The meeting ends of said flanges are fastened together by the corner fasteners 26.

A suitable grip 27 is carried by the outer surface of the front closure 5 of the body 90 by means of which the case can be readily handled.

It will be seen from the foregoing that the improved filing case being formed of cardboard, the same can be economically manufactured, and is also light in weight.

In use, the pressure of the papers or other material held in the body by the stop 16 will cause said stop to incline so that it will bind upon the side guide strips. To adjust 100 said stop, the hand can be inserted through the open rear end of the box and the stop rocked to a vertical position and then readily adjusted.

What I claim as my invention is:— 105

1. A filing case comprising a body formed of integral sides and bottom, a front closure for said body, a cover for said body, guide strips carried by the sides and bottom, and a stop slidably engaging said strips. 110

2. A filing case comprising a body having an open rear end and top, a closure for the

front end of said body, a cover for the top of said body, a longitudinally arranged guide strip carried by the bottom of said body, horizontally arranged oppositely disposed guide strips carried by the sides of said body, and a stop slidably engaging said strips.

3. A filing case comprising a body, a cover therefor, spacer blocks carried by the bottom of said body, a guide strip held in spaced relation to the longitudinal center of said bottom by said blocks, spacer blocks carried by the sides of said body, horizontal guide strips held in spaced relation to the sides of said body by said blocks, and a stop slidably engaging said strips.

4. A filing case comprising a body formed of integral sides and bottom, the forward edges of said sides and bottom provided with flanges, a front closure rigidly fastened to said flanges, a flange at the rear

edges of said bottom, flanges at the lower portions of the rear edges of said sides, a guard strip rigidly fastened to the said rear flanges, flanges at the upper portion of the rear edges of the sides, a guard strip rigidly fastened thereto, a cover for said body, and a stop slidably in said body.

5. A filing case comprising a body, guide strips held in spaced relation to the sides and bottom thereof, and a stop provided with side and bottom openings through which said strips extend and also with side and bottom flanges which lie beneath said strips.

In testimony whereof I affix my signature in presence of two witnesses.

HERBERT H. SELLERS.
